UNITED STATES PATENT OFFICE.

GEORGE F. BUTTERFIELD, OF STONEHAM, MASSACHUSETTS.

DESIGN FOR A BATH-TUB.

SPECIFICATION forming part of Design No. 23,973, dated January 29, 1895.

Application filed December 20, 1894. Serial No. 532,503. Term of patent 14 years.

To all whom it may concern:

Be it known that I, GEORGE F. BUTTERFIELD, of Stoneham, in the county of Middlesex and State of Massachusetts, have invented and produced a new and original Design for a Bath-Tub, of which the following is a specification.

Reference is to be had to the accompanying drawing, forming a part of this specification, in which the figure is a perspective view of a bath tub showing my design.

The leading feature of my design consists in the widened head portion A, and the ordinary foot end B.

A minor feature of my design is the seat C 15 on the upper edge of one side of the foot end adjacent to and terminating at the widened part of the head portion A.

A further minor feature of the design is the transverse partition D, between the head portion A and the foot end B. 20

I claim—

The design for a bath tub as shown and described.

GEORGE F. BUTTERFIELD.
